UNITED STATES PATENT OFFICE.

ADOLPH PETELE, OF FREEPORT, NEW YORK.

TIRE-PUMP.

1,236,479.

Specification of Letters Patent. Patented Aug. 14, 1917.

Application filed August 16, 1916. Serial No. 115,192.

To all whom it may concern:

Be it known that I, ADOLPH PETELE, a citizen of the United States, residing at corner of Rosedale street & Broadway, Freeport, county of Nassau, and State of New York, have invented certain new and useful Improvements in Tire-Pumps, fully described and represented in the following specification and the accompanying drawings, forming a part of the same.

The object of this invention is to furnish a construction for an air-pump by which the piston of the pump may be moved rapidly for a greater part of its stroke and moved more slowly and with concentrated force at the end of its stroke, and to effect such result with simple and inexpensive mechanism.

The construction includes a cylinder having pivots at one end fitted movably to parallel guides upon one end of a bed, a lever fulcrumed upon the opposite end of the bed and having arms projected in opposite directions, one arm being linked to the cylinder-pivots to move them forward in the guides, at the same time that the opposite arm of the lever presses the piston-rod into the cylinder.

The lever and piston-rod form two members of a toggle, so that the closing movement of the piston exerts a great compressing force upon the air, while the forward movement of the cylinder makes the initial movement of the piston much more rapid and less powerful.

This construction is shown embodied in a foot-pump, in which the bed is adapted to rest upon the floor, and the lever provided with one long arm which is held normally raised by a spring into such a position that the foot can be readily applied to it to press it downward.

Repeated movements of the foot thus compress the air in the cylinder and discharge it from the outlet.

To centralize the strains upon the various parts, the lever and its connections are made duplex, the lever being formed of two plates pivoted to opposite sides of the lever bracket, and the shorter arms of its plates connected by duplex-links with the pivots upon the cylinder thus operating to move them both simultaneously in duplex guides upon the bed.

The arms of the lever are spaced apart sufficiently to pass downward at opposite sides of the cylinder, and the piston-rod is

provided with a cross-head which is jointed to the duplex lever-arms, and when the lever is wholly depressed such joint stands in a line between the pivots of the cylinder and the fulcrum of the lever so as to straighten the toggle composed of these parts and compress the air with the greatest force.

The invention will be understood by reference to the annexed drawing, in which Figure 1 is a side elevation of the pump; Fig. 2 a plan of the piston cross-head; Fig. 3 an elevation of the latch for the same; Fig. 4 a side elevation of the pump with the lever depressed; Fig. 5 is a plan of the pump in the same position as in Fig. 4; and Fig. 6 is a plan of the bed.

A is the bed having duplex parallel guides *a* attached to its opposite edges at the rear end, and a lever bracket *b* projected upward upon its opposite end.

The guides *a* have slots *a'* which extend lengthwise of the bed, and the cylinder *d* has pivots *c* at the opposite sides of its base or rear end, which extend through the slots *a'* and are jointed to links *f*.

The cylinder has the usual valve-box *c'*, from which a hose *d'* may be extended to deliver the air.

The power-lever is formed of side-plates *g* each having a longer arm *g* and a shorter arm *g'* extended in opposite directions from the fulcrum *h* upon the bracket.

The cylinder is provided with a piston-rod *i* to operate an inner piston in the usual manner, and a cross-head *j* is fixed upon the end of the piston-rod and is jointed by pivots *k* at its ends to the opposite lever-bars *g*. The lever-arms are extended beyond the pivots *k* for a sufficient distance to carry a tread or foot-plate *l*, thus giving the foot a leverage over the cross-head *j*.

The links *f* are jointed to the ends of the shorter lever-arms *g'*, and the movement of the power-lever from its raised position shown in Fig. 1 to the depressed position shown in Fig. 4 operates simultaneously to draw the links and the cylinder toward the fulcrum *h* of the lever, while the arm *g* operates to push the piston-rod in the opposite direction.

The first part of the movement, as will be apparent from Fig. 1, forces the piston very rapidly, but the last of the depressing movement brings the piston cross-head down into a direct line between the lever-fulcrum *h* and the cylinder pivots *c*, which straightens

the toggle formed by these members, and presses the piston-rod into the cylinder with the greatest force.

- A spring m is shown wound upon the fulcrum of the lever and formed with a central loop to rest upon the seat n on the bracket b , while the coils of the spring extending oppositely are terminated in fingers m' , which are fitted beneath the arms g of the power-lever and operate to press the same normally upward, as shown in Fig. 1. This movement is limited by the contact of the cylinder-pivots c with the outer ends of the slots a in the pivot-guides. The movement of the power-lever in the opposite direction by foot or hand-pressure, is limited by the contact of stops r upon the foot-plate l with the top of the two side links f , as shown in Fig. 4.
- 20 A latch p having a T-shaped head p' is provided to hold the power-lever thus depressed when it is desired to transport or store the pump. Such latch is jointed at o upon a rib of the bed and extended upward past the front edge of the cross-head j , which is provided with a notch e , shown in Figs. 2 and 5, into which the upper end of the latch may be slipped and retained therein by the T-head.
- 25 It will be observed that the side-bars of the power-lever are thin flat pieces which may be readily stamped from sheet-metal of suitable thickness, as well as the links f and the slotted guides a . These parts may thus 30 be very cheaply constructed and connected together with a minimum of labor, thus producing a cheap construction which is also most effective in compressing the air.
- Having thus set forth the nature of the 35 invention what is claimed herein is:
1. In an air-pump, the combination, with a bed-piece having parallel guides at one end and a lever-bracket upon the opposite end, of an air-cylinder with pivots movable in the parallel guides and having a piston-rod, and a power-lever having a fulcrum upon said bracket connected at opposite sides of the fulcrum respectively to the cylinder-pivots and the piston-rod, to move 40 the same simultaneously in opposite directions.
  2. In an air-pump, the combination, with a bed-piece having parallel guides at one end and a lever-bracket upon the opposite end, of an air-cylinder with pivots movable in the parallel guides, a power-lever having a fulcrum upon said bracket with arms projected at opposite sides of the fulcrum, the shorter arm having links connected to the 45 pivots of the cylinder, the longer arm having a piston-rod cross-head jointed thereto to operate a piston in the cylinder, and the longer arm projected beyond such cross-head for application of power thereto.

3. In an air-pump, the combination, with a bed-piece having duplex parallel guides at one end and a lever-bracket upon the opposite end, of an air-cylinder with pivots movable in the parallel guides and having a piston-rod with cross-head on the end of the same, a duplex-lever having a fulcrum upon said bracket with arms projected at opposite sides of the fulcrum, the shorter arms having duplex links connected to the pivots of the cylinder to move them in the slots, and the longer arms being pivoted to the cross-head of the piston-rod, the oscillation of such duplex-lever operating to move the cylinder and piston-rod toward one another.

4. In an air-pump, the combination, with a bed-piece having parallel guides at one end and a lever-bracket upon the opposite end, of an air-cylinder with pivots movable in the parallel guides and having a piston-rod with cross-head upon the end, a power-lever having a fulcrum upon said bracket connected at opposite sides of the fulcrum respectively to the cylinder-pivots and the piston-rod, a spring attached to the bed to press the power-lever normally away from the same, and a latch upon the bed adapted to engage the power-lever when pressed toward the bed and hold the same in a compact condition.

5. In an air-pump, the combination, with a bed-piece having duplex parallel guides fastened upon its edges at one end and a lever-bracket upon the opposite end, of an air-cylinder with pivots movable in the parallel guides and having a piston-rod with cross-head upon its end, a duplex power-lever having a fulcrum upon the bracket with two side-arms projected at opposite sides of the fulcrum, duplex-links connecting the shorter lever-arms with the cylinder-pivots and the longer lever-arms jointed to the cross-head of the piston-rod.

6. In an air-pump, the combination, with a bed-piece having parallel guides at one end and a lever-bracket upon the opposite end, of an air-cylinder with pivots movable in the parallel guides and having a piston-rod, a power-lever having a fulcrum upon said bracket connected at opposite sides of the fulcrum respectively to the cylinder-pivots and the piston-rod, a spring operating to press the power-lever normally from the bed and a latch connecting the bed and the power-lever at pleasure to hold the same close to the bed.

7. In an air-pump, the combination, with a bed-piece having parallel guides at one end and a lever-bracket upon the opposite end, of an air-cylinder with pivots movable in the parallel guides and having a piston-rod with a cross-head upon its end, a duplex power-lever having a fulcrum upon the

bracket with two side-arms projected at opposite sides of the fulcrum, duplex-links connected to the shorter lever-arms and extended by the sides of the cylinder to its 5 pivots and the longer lever-arms being jointed to the cross-head of the piston-rod and extended over the air-cylinder and hav-

ing a foot-piece moving toward the links when depressed with stops upon the foot-piece adapted to contact with the links. 10

In testimony whereof I have hereunto set my hand.

ADOLPH PETELER.
